CLAIM

The ornamental design for an image display device, as shown and described.

DESCRIPTION

FIG. 1 is a right-side perspective view of an image display device;

FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof; and,

FIG. 8 is a left-side perspective view thereof.

The broken lines depict unclaimed portions of the image display device and form no part of the claimed design.
